SHEET OF ABRASIVE MATERIAL

Bulkeley F. Winslow, Brookline, Mass., assignor to
 United Shoe Machinery Corporation, Borough
 of Flemington, N. J., a corporation of New
 Jersey

Application May 15, 1939, Serial No. 273,733

4 Claims. (CL 51—190)

This invention relates to sheets of abrasive material prepared in such manner that they may be shipped to the user and readily applied by him to their intended use. While the invention is illustrated with reference to abrasive sheets intended as the work treating elements of buffering rolls commonly employed in shoe and leather work, it is to be understood that the sheets may be applied to other rolls and for other purposes.

It is an object of the invention to provide abrasive sheet material ready for instant application to buffering rolls without the necessity of providing any securing means other than that carried by each sheet of such material. It is a further object of the invention to provide adhesive layers along end margins upon opposite surfaces of each sheet of a character such that such end margins will instantly be bonded together merely by pressure, thus reducing to a minimum the time and effort necessary to secure the abrasive material in place on a buffering roll. Further objects of the invention are to provide an abrasive sheet that will be ready for operation the instant it has been secured in place on a roll, by pressure upon such adhesive-carrying marginal portions of the sheet, and further to provide a joint which will be strong enough to maintain the abrasive sheet in position and in perfect condition for its intended use and at the same time flexible, thus minimizing any tendency to a hard resistant area at the location of said joint.

To these ends, and in accordance with an important feature of the invention, a quadrilateral sheet of abrasive material is provided along opposite marginal portions and on opposite sides of the sheet with layers of adhesive material covered by protective strips readily removable to uncover tacky surfaces on the adhesive layers which need no activation but which will firmly adhere to each other instantly upon suitable pressure, thereby facilitating the application of the abrasive sheet material to a roll or other cylinder suitable for buffering, sanding or scouring purposes.

In a preferred form of the invention, a sheet of paper having a surface layer of abrasive material on one side only is provided along an abrasive marginal portion thereof with a layer of rubber cement of a consistency to fill in the abrasive surface of such marginal portion of the sheet and to effect a strong bond with such surface, said sheet having also a layer of rubber cement applied to the plain surface of the sheet along a marginal portion opposite to the first-mentioned marginal portion. Subsequently both cement layers are covered by a layer of latex which is

allowed to dry for a suitable time, the latex layers being then covered by protective strips of suitable material, such as Cellophane, the latter serving to protect the tacky surface of the latex and keep it in good condition so that the latex layers will instantly become bonded to each other upon being superposed and subjected to pressure. This abrasive sheet with its protected, pressure-responsive layers of adhesive constitutes an article of manufacture a plurality of which may be readily stacked and packaged for shipment, since the adhesive-carrying edges are protected or masked so that there will be no adhesion between adjacent sheets in the stack.

Other advantages of the described article reside in the fact that each sheet is ready for instant application to its intended use simply by removing the protective strips from the marginal portions of the sheet just before such marginal portions are brought into contact with each other. Since the adhesive layers need no activation by solvent or by heat or otherwise, such adhesive portions may be instantly united simply by pressure and the roll thus provided with an abrasive covering may be immediately put into operation. Because of the strong bonding union between the overlapped and underlapped marginal portions of the abrasive sheet, no other means is needed to hold the abrasive covering on the buffering roll. Hence, the latter may present a smooth unbroken surface in sharp contrast to buffering rolls heretofore commonly provided for commercial purposes, particularly for operations upon shoes and tanned hides and skins.

With these and other objects and advantages in view the invention will now be described in detail in the specification and then pointed out more particularly in the appended claims.

In the drawing,

Fig. 1 is a plan view of a quadrilateral sheet of abrasive paper having protected layers of pressure-responsive adhesive applied to opposite marginal portions of the sheet on opposite sides thereof;

Fig. 2 is an enlarged sectional view taken along the line II—II of Fig. 1, the view being schematic, not actual;

Fig. 3 is a package of sheets, each of the construction shown in Fig. 1; and

Fig. 4 is a rubber-covered roll having a sheet of abrasive paper secured in place on the cylindrical surface of the roll by having its adhesive-carrying edges lapped and pressed together.

In the illustrated article, which is specially designed for use on buffering rolls, there is shown a

rectangular sheet of paper 10 having a suitable abrasive material 11 uniformly disposed over one side thereof, the other side of the sheet being plain and even, since it is to contact the cylindrical surface of a roll 12 suitable for buffing, sanding or scouring operations. Applied to a marginal portion 14 of the abrasive surface is a layer of rubber cement 16, the cement being of a consistency and of sufficient quantity to fill in substantially the abrasive surface and provide a practically even surface, in spite of the fact that the abrasive material over the surface of the sheet presents an uneven surface with spaces between upstanding abrasive particles designed to abrade a work piece. After the rubber cement has dried sufficiently, the time required being two or three minutes in a heated chamber, a layer 18 of latex is applied over the rubber cement layer 16, the latex further filling in any low spot left unfilled by the cement. This latex layer is allowed to dry about the same length of time as the rubber cement layer to provide a tacky surface which is then promptly covered by a protective strip 20 of a suitable material, such as Cellophane, which will not adhere too strongly to the latex surface. Similar layers of rubber cement and of latex are applied in the order described to the opposite marginal portion 22 of the sheet 10 and to the opposite side of the sheet, that is, to the plain surface, as distinguished from the abrasive-carrying surface. Any slight inequalities which may remain on the margin 14, after the application of the cement and latex layers, as when an exceptionally coarse abrasive material is employed, become embedded later in the latex and cement layers on the plain-surfaced margin 22 when the adhesive-carrying margins 14 and 22 are bonded together, as will be readily understood. Subsequently a strip of Cellophane 20 is applied over the latex layer on the marginal portion 22 of the sheet. Since the abrasive sheet material, when thus prepared, has its adhesive-carrying edges protected by strips of Cellophane, there is provided an article a number of which may be packaged in a stack of any suitable size preliminarily to distribution to users of buffing, sanding or scouring machines.

In providing an adhesive for securing together opposite marginal portions of a sheet of abrasive material, I have utilized a rubber cement which forms an excellent bond with both the plain paper surface and with the abrasive surface, in the latter case also filling in the spaces between the abrasive particles to make a substantially even surface to which the protective strip will adhere with sufficient firmness so as not to be prematurely displaced therefrom. While any suitable rubber cement may be used, I have found that a rubber cement which contains rosin and reclaimed rubber gives excellent results. The rubber cement not only makes a better bond with the paper but it has no disadvantageous effect thereon, whereas, the latex, if applied directly to the paper, would wet the latter with the result that wrinkles would subsequently be formed in the paper. By applying a layer of latex to the properly dried rubber cement layer, and allowing the latex to dry for a suitable period, there is provided a pressure-responsive adhesive layer (completely bonded with the rubber cement) that needs no activation. Incidentally, many adhesives need the application of heat or of a solvent to be properly activated when the time comes for effective union with a similar layer of adhesive in making a bond between given surfaces.

The strip of Cellophane has been found to adhere sufficiently to the latex layer to insure against premature displacement, while at the same time it may be readily stripped from the latex surface when the bonding of the two latex surfaces is to take place.

Preferably, the abrasive sheet material will be applied to a roll 12 (Fig. 4) having a layer of rubber 24 cemented to the surface of a metal roll 25, the meeting edges of the rubber layer being indicated by the dotted line 26. It is to be understood, of course, that the rubber layer may be secured to the metal cylinder by any other well-known means.

In order to apply an abrasive sheet like that shown at 10 to the cylindrical surface of the roll 12, the sheet is wrapped around the roll with the abrasive-carrying surface on the outside. With the sheet in the desired position the strips of Cellophane are readily peeled from the marginal portions to be lapped, the margin 22 being the overlapping margin, and manual pressure is applied along the length of said lapped marginal portions. When the marginal portions 14 and 22 have been properly applied to each other, and a bond formed in the adhesive layers through the pressure applied to said marginal portions, the abrasive covering is not only secured in place on the buffing roll but it is ready without delay for effective work as an abrasive. The initial bond thus obtained is adequate to hold the lapped margins from separating under the usual working conditions, it being pointed out that, even if the lapping of the adhesive margins and the applying of manual pressure thereto be carelessly and hastily performed, the bond is perfected by the pressure of the work piece held in engagement with the abrasive surface while the tool is rotated. It will be found that the joint thus formed between the overlapping marginal portions of the abrasive cover is permanent, at least, from the standpoint of its intended service. Furthermore, the joint thus formed by this pressure-responsive adhesive is a flexible one, thus minimizing the effect of thickness due to overlapping layers of sheet material and of adhesive at the location of the joint. When it is desired to remove this abrasive sheet at the end of its effectiveness as an abrasive on the buffing roll, it is necessary only to slit the paper at a suitable point, for instance, along the dotted line 26 where the edges of the rubber layer come together, or to tear the paper off the roll, whereupon a new abrasive cover may be applied in the manner already described.

The abrasive sheets 10 will be sold in suitable packages such as that shown at 30 in Fig. 3, wherein a stack of twenty-five sheets are shown held in packaged form by a binder 32 which may be readily cut or broken to release the sheets 10 for use.

Having described my invention, what I claim as new and desire to secure by Letters Patent is:

1. An article of manufacture comprising a sheet of material having an abrasive coating upon one of its surfaces and having its end margins upon opposite surfaces of the sheet provided with a layer of pressure-responsive adhesive material to enable said end margins to be joined in lapped relation, said adhesive material covering the grains of abrasive material and substantially filling the spaces between them, said adhesive material also having flexible and resilient properties to contribute to the making of a yieldable joint without requiring removal of the abrasive coating at the joint.

2. An article of manufacture comprising a sheet of material having a surface layer of abrasive material on one side only and having further a layer of rubber cement applied to a marginal portion of the abrasive surface of the sheet to cover the grains of abrasive material and substantially fill the spaces between them and having also a rubber cement layer applied to an opposite marginal portion and on the plain surface of the sheet, said sheet having further a layer of latex applied over each rubber cement layer, whereby the adhesive-carrying marginal portions of the sheet may be instantly united, when properly superposed, merely by pressure to secure a firm bond between such superposed marginal portions of the sheet to secure the latter in place on a roll or other buffering tool, the rubber and latex layers being flexible and resilient and thus contributing to the making of a yieldable joint in the overlapped portions of the abrasive sheet despite the presence of abrasive material in the joint.

3. Method of rendering a marginal portion of an abrasive sheet strongly adhesive in response to pressure, which consists in filling in the irregularities of the abrasive marginal surface with rubber cement to provide a substantially even cement surface, permitting the cement to set, and then applying to the even surface of cement a pressure-responsive coating of latex.

4. Method of rendering opposite end margins at reverse sides of an abrasively coated sheet strongly adhesive to each other in response to pressure, which consists in first applying to said margins a coating of rubber cement, the coating on the abrasive side of the sheet being sufficient to fill in the irregularities of the abrasive surface to provide a substantially even surface of cement, and then, after the cement has set, superimposing thereon a pressure-responsive coating of latex.
